UNITED STATES PATENT OFFICE

ROMAN F. POLSKI, OF ST. PAUL, MINNESOTA

IRONING BOARD

Application filed June 19, 1926. Serial No. 117,139.

It is my object to provide an ironing board of simple and durable construction, adapted to be quickly collapsed for storing in compact form and having a supporting structure adapted to render the board unusually stable when in use.

My invention also includes certain other novel features of construction, which will be more fully pointed out in the following 10 specification and claim.

The invention will be best understood by reference to the accompanying drawings, in which Figure 1 is a side elevation of my improved board in position for use; Fig. 2 is a 15 front elevation of the same; Fig. 3 is a fragmentary section taken on the line 3—3 of Fig. 1 and Fig. 4 is a section taken on the line 4—4 of Fig. 3; Fig. 5 is a side elevation of an alternate form of my device; Fig. 6 20 is an end view of the same; Fig. 7 is a bottom plan view showing the supporting structure collapsed and Fig. 8 is a detail showing the spring catch and abutment for one end of a pair of the leg members.

As illustrated, my device has an ironing board top 9 of usual form having a pointed 25 end 10 and the opposite end 11 extending at right angles to the longitudinal sides of the board. Secured to the bottom surface of the 30 top 11 in parallel relation with the end 11 is a transverse bar 12. A pair of leg members 13 are pivotally connected with the ends 35 of the bar 12 by stud bolts 14. These bolts project from the outer faces of the leg members 13 and are adapted to be supported in brackets 15. Slots 16 extend downward in the brackets 15 to receive the stud bolts 14, as best shown in Fig. 4.

A cabinet 17 is adapted to be mounted 40 upon a wall or set in a recess therein to receive the top 9 and leg members in collapsed position. The brackets 15 are secured upon the inner surfaces of a pair of vertical side members on the cabinet 17 near the lower 45 ends of said members. It will be evident that a door may be provided to close the outer, normally open side of the cabinet and thus conceal the ironing board when folded into the cabinet.

In the preferred form of my device, shown

in Figs. 1 and 2, the leg members 13 extend in parallel relation one with the other and are secured together by means of a transverse brace 18. At their normally lower ends, the leg members 13 are also further connected by a transverse rod 19. This rod 19 also forms a pivotal connection with a second pair of leg members 20, which are spaced apart at their lower ends by the rod 19 and converge toward their upper ends. The normally upper ends of the members 20 are connected by a pin 21, being held in spaced relation thereby to receive a retaining member 22 between them. As shown in detail in Fig. 8, the retaining member 22 is provided with a resilient finger 23, adapted to hold the pin 21 between it and the bottom surface of the top 9. A stop or abutment 24 projects beneath the finger 23 for engagement with the pin 21. As illustrated, the member 22 is 60 formed from a block of suitable wood, secured to the bottom surface of the top 9 by screws and having a slot 25 extending in from one end to form the resilient finger 23.

In the alternate form of my device, shown 65 in Figs. 5, 6 and 7, the top 9, pivotal connection between the legs 13 and top, and members 12 and 22 are identical with that shown in the preferred form, but the legs 13 and 20 are arranged to converge downward and 70 inward, the leg members 20 being separated at their normally upper ends by a pin 26, adapted to be forcibly pressed beneath the 75 spring finger 23. The leg members 13 in the alternate form are connected by a transverse 80 brace member 27 and a pin 28 extends through the normally lower extremities of 85 said leg members and the abutting ends of the leg members 20. To rearrange the leg member 20 from the position in the preferred 90 form to that in the alternate form, it is only necessary to substitute one of said leg members for the other, to replace the rod 19 by the shorter pin 28 and to replace the short 95 pin 21 by the longer pin 26.

In use, the cabinet 17 is rigidly secured upon a wall in the position shown in Figs. 1 and 2, or it may be built into the wall. The ironing board is attached to the cabinet 17, by merely dropping the stud bolts 14 into

the slots 16 in the brackets 15. Now to support the top 9 in the rigid condition for use, as shown in Figs. 1 and 2, the leg members 13 and 20 are pivoted upon the bolts 14 to the position shown in Fig. 1 and the pin 21 is forcibly pressed beneath the resilient finger 23 and against the stop 24. It will now be evident that one end of the top 9 is rigidly supported on the cabinet 17 and the weight of the other end is sustained upon the floor by the leg members 13 and 20. To store the ironing board in compact form, it is only necessary to withdraw the pin 21 from engagement with the finger 23 and to fold the leg members 13 and 20 flat upon the normally bottom surface of the top 9, as indicated in dotted lines in Fig. 2. The collapsed board may now be folded upward into the cabinet 17 by pivoting upon the bolts 14, as shown in dotted lines in Figs. 1 and 2.

My improved ironing board may be readily removed from the cabinet 17 and the top 9 with its supporting leg members 13 and 20 may be readily transported from one part 25 of a dwelling to another. When removed from the cabinet, the end 11 of the top 9 may be rested upon any convenient table or other support of suitable height, such as the table 29 shown in Fig. 5. Thus, after erecting 30 the legs 13 and 20, the end 11 of the board top 9 may be placed upon a margin of the table top, so that the bar 12 abuts against the edge of the table. Now the legs 13 and 20, by reason of their oblique position, maintain the ironing board firmly against the edge 35 of the table. The greater part of the weight is carried by the legs 13 and 20, which, by reason of their converging arrangement, form a rigid and stable support, whether the top 40 is connected at one end of the cabinet 17 or supported upon a table like the table 29.

It will be understood that the relatively short legs 20 are the compression members, carrying the greater part of the weight, and the legs 13 act as tension members which maintain the legs 20 in fixed, inclined position, such that the pin 21 (or rod 26) is always thrust firmly against the stop 24 under weight applied to the top 9. The legs 13 also 45 form the important function of preventing side rocking or swinging movement of the legs 20 when in use. Thus, the legs 13 form with their cross braces a rigid structure, preventing sideward movement of the lower end 50 of the legs 20.

Having described my invention what I claim as new and desire to protect by Letters Patent is:

In an ironing board, the combination with 60 a housing, adapted to be supported upon a wall, brackets attached to opposite sides of said housing, an ironing board top adapted to extend at one end between said brackets, laterally projecting studs pivotally joining 65 said top near one end to said brackets, a pair

of oblique legs pivoted at one end upon said studs and adapted to extend obliquely beneath said top, a second pair of legs pivotally joined to the lower ends of said first mentioned legs and diverging upward relative to said first mentioned legs to support said top intermediate its ends and means detachably connecting the upper ends of said second pair of legs to said top, both pairs of legs being arranged to be collapsed upon the bottom of said top for folding in compact form into said housing, and said studs being adapted to be readily removed from said brackets to permit the ironing board to be detached from the housing.

In testimony whereof, I have hereunto signed my name to this specification.

ROMAN F. POLSKI.
